UNITED STATES PATENT OFFICE.

HENRY WEBER, OF CHICAGO, ILLINOIS, ASSIGNOR TO LATHAM MACHINERY COMPANY, OF CHICAGO, ILLINOIS, A CORPORATION OF ILLINOIS.

WIRE STITCHING OR STAPLING MACHINE.

1,111,115.

Specification of Letters Patent. Patented Sept. 22, 1914.

Application filed August 16, 1911. Serial No. 644,374.

To all whom it may concern:

Be it known that I, HENRY WEBER, a citizen of the United States, residing at Chicago, in the county of Cook and State of Illinois, have invented certain new and useful Improvements in Wire Stitching or Stapling Machines, of which the following is a full, clear, and exact specification.

This invention relates to wire stitching or 10 stapling machines of the class shown in my United States Letters Patent, Numbers 683,821 and 683,823, issued October 1st, 1910, in which the staple, preparatory to being driven or engaged by the driver after the 15 withdrawal of the anvil, is sustained by a supporter; and the improvements have more especial reference to such supporter and associated parts, and has for one of its objects to provide a wire stitching or stapling 20 machine having staple supporting means which shall be simple and compact in construction and effective in operation.

The improvements also relate to the means 25 for guiding and holding the staple forming and staple driving devices, and the invention has for its further object to provide improved means for this latter purpose which will permit of the ready removal and inspection of such devices.

30 The invention consists in the features of novelty described in the following specification, shown in the accompanying drawings and particularly pointed out in the claims.

In the said drawings which illustrate an 35 example of the invention, Figure 1 is a front elevation of a portion of a wire stitching or stapling machine embodying this invention; Fig. 2 is a detail perspective view of the staple supporter and its hanger; Fig. 3 is a 40 vertical section taken on the line 3—3 Fig. 1; Fig. 4 is a vertical section on line 4—4 Fig. 1; Fig. 5 is a detail perspective view of the wire guide; Fig. 6 is a horizontal plan section on the line 6—6 Fig. 4; and Fig. 7 45 is a horizontal plan section on irregular section line 7—7 Fig. 4.

8 is a part of the main frame of a wire stitching machine upon which the devices for forming and driving the staple, together 50 with their operating mechanism, are mounted, the same usually comprising, and in this example of the invention preferably comprises, an anvil 9, a former 10, a driver 11, and a supporter 12, associated with a suitable cam 13 for operating the former, and a 55

crank 14 for operating the driver through the intermediary of pitmen 15, 16 being the cam shaft, which may be journaled in the frame 8 or other suitable part of the machine, as usual.

As the wire is advanced through the anvil 9 which is provided as usual with slot 17 for the reception of the wire, it is pushed back into its seat by a wire guide shown in detail in Fig. 5, and consisting of an arm 18 supported by pivot 19 and having an inclined face 20, arranged to be engaged by the tip of the wire as it is advanced through the slot of the anvil, the wire guide being of the usual or any suitable construction, and held 60 up to its work by spring 21, or other suitable means. The wire being properly placed in the slot of the anvil, it is then engaged by the bifurcated wire former 10, the end of the wire having been previously severed, and 65 both extremities of the severed portion are thus bent downwardly into a substantially U shape by the former, which straddles the anvil and is provided with grooves in the inner faces of its branches, as usual, for 70 guiding the driver 11, which it embraces and also engaging and holding the wire while being formed and driven. As the 75 driver 11 descends in the act of engaging and driving the staple, it first engages with the inclined top face of the anvil 9, as 80 usual, and forces the same longitudinally out of its path and eventually engages and drives the staple downwardly while the 85 branches of the staple are supported against inward, bending in co-operation with the grooved branches of the former, by the supporter 12, which is also engaged by the 90 driver 11 and forced backwardly out of the way as the staple proceeds downwardly, the 95 staple supporting end of the supporter 12 being provided with a curved face 23, terminating in a point 24, which is the last portion of the supporter to withdraw from the 100 embrace of the staple, and the lower face of the supporter is struck on a suitable arc 25, so that as the supporter swings backwardly out of the way of the driver the point 24 105 will be brought into close propinquity to the surface into which the staple is being driven. As the driver rises from the driven staple the supporter 12 is returned to its former position by any suitable means such as a spring or other elastic element 26, while the anvil 9 is replaced by the spring 27, 110

which, together with the spring 26, serves to keep the end of the anvil and the curved surface 23 of the supporter 12 in close relation during the staple forming and driving operations. In this example of the invention the anvil 9, shown in connection therewith, is of a familiar type, arranged in a horizontal position in a suitable socket 28, containing also the spring 27, the anvil being held against rotary action by a guide pin 29 in the usual way. An anvil of any other suitable form, however, may be employed.

The staple supporter 12 is connected by means of a pivot 30 to the lower end of a hanger 31, which serves to sustain the supporter in position. According to this invention, the hanger 31 is composed of a substantially straight rod or block provided at one end with a pair of lugs 32, by means of which the hanger is given support upon the former 10, which is provided with shoulders 33 for the purpose, such shoulders being formed by recesses 34 in the sides of the former, which are extended in an upward direction to permit of a limited range of movement of the former independently of the hanger 31, so that while the supporter 12 is resting contiguous to the surface into which the staple is being driven, the former 10 may continue its downward movement in the act of forming the staple over the anvil. The bar 31, which may conveniently be rectangular, in cross section, is slidably housed in a cap 35, in the lower end of which is a recess 36 for accommodating the supporter 12, so that when the cap 35 is removed the lugs 32 may be simply disengaged from their recesses 34, and the supporter and its hanger 31 removed from their guide way in the cap 35, the same being held therein preferably without any other attaching means. The cap 35 may, of course, be held in place by screws 37, or other suitable devices. The hanger 31 also constitutes a housing for the supporter spring 26. To that end the hanger is provided with a socket 38, which may be conveniently formed by a drill, for receiving the spring, and also a plunger 39 which may be of cylindrical form, with its lower end protruding from the socket of the hanger and provided with suitable bearing point 40, shown in this example of the invention as hemispherical, engaging the supporter 12, which has a rounded face 41, upon which the bearing point 40 rests, and by which the supporter 12 is held up to its work, contiguous to the anvil 9 under the influence of the spring 26. The plunger 39 is held against accidental discharge from its socket 38 by a pin 42, engaging in a groove 43 in the plunger.

The former 10, containing the driver 11, is housed within a guide box 44, suitably supported on the frame member 8, and pro-

vided with a passage or groove 45 for receiving and guiding the former. Both the exterior sides of the former and the guide walls of the groove 45 are preferably parallel, both transversely and longitudinally, so that the former together with the driver may be removed transversely from the front of the box 44 when the cap 35 is removed. The outer edge or face of the former is flush with the face of the box 44, as better shown in Figs. 6—7, and the hanger 31 whose rear face is straight and flat, fits against the outer face of the former 10, and is thereby held against undue inward movement, while it is held against outward movement as well as lateral movement by the cap 35, which latter also overlaps the outer face of the former for preventing the latter from moving outwardly.

The wire guide 18 is also preferably mounted in a recess 46 in one side of the cap 35, containing also the wire guide spring 21, so arranged that the wire guide may recede into the recess 46 entirely out of the way of the former and driver when they descend. Thus it will be seen that when the cap 35 is detached the former and driver may be readily removed from their guide box 44, the pitmen 15 being first disconnected, and the supporter 12 and its hanger 31 may be as readily removed from the cap 35 with the supporter spring 26 and plunger 39 intact. It will also be seen that by thus arranging the supporter spring within the hanger bar 31, or in position contiguous to and substantially parallel with the driver and former, certain protruding parts heretofore employed in front of the machine for supporting the spring are dispensed with, leaving the front of the machine free and unobstructed.

What I claim is:

1. The combination with staple forming and driving members, of a block mounted thereon, a staple support pivoted to said block arranged to swing at predetermined intervals into the path of said forming and driving members, and a spring actuated plunger mounted in said block and arranged to bear against said staple support for imparting a movement thereto when the path of swing of said staple support is unobstructed.

2. The combination with staple forming and driving members, of a block coöoperating with and located adjacent thereto, a support pivoted to said block, and a spring actuated plunger mounted within said block parallel to one of the vertical faces thereof and arranged to operate against said support to force the same into the path of movement of the staple forming and driving members at predetermined intervals.

3. The combination with staple forming and driving members, of a block coöperat-

- ing with and located adjacent thereto, a support pivoted to said block, a spring-actuated plunger mounted within said block and arranged to operate against said support and force the same into the path of movement of the staple forming and driving members at predetermined intervals, and means for limiting the movement of said plunger.
4. The combination with a frame, of a staple former and driver mounted therein, a cap secured to said frame provided with a projection having a longitudinal passage therein, said passage having a transverse enlargement at the lower terminal thereof, a hanger mounted for reciprocation in said passage, means for reciprocating said hanger from the former aforesaid, a staple supporter pivotally connected to the lower end of said hanger and mounted within the enlargement aforesaid and contained wholly within the cap, and means mounted within said hanger for forcing said supporter into the path of the staple former and the driver at predetermined intervals.
5. The combination with a staple former, elongated recesses formed on each side of said former, a block located adjacent to said former, lugs carried by the upper terminal of said block adapted to be received in said recesses whereby the former may have a movement independently of said block, a staple support pivoted at the lower end of said block, and automatic means contained entirely within said block whereby said staple support is caused to swing into the path of said former at predetermined intervals.
6. In combination with a former and a driver, a cap covering the same having a longitudinal passage therethrough and an enlargement in said passage at the lower terminal thereof, a hanger mounted in said passage arranged to be operated vertically by said former, and having a passage in the lower terminal thereof, a spring-pressed plunger mounted in said passage, and a staple supporter mounted on the lower terminal of said hanger, said staple supporter being segmental in formation and extending into the enlargement aforesaid, the portion thereof in said enlargement being operated upon by the spring-pressed plunger.
7. The combination with a block, of a quadrental support pivoted at the lower terminal thereof, said support having the convergent faces thereof curved inwardly, a plunger mounted in said block, a spring mounted in said block, and a plunger acted upon by said spring and bearing against one of the curved edges of said support and adapted to force the latter automatically in a given direction at predetermined intervals.
- In testimony whereof I have signed my name to this specification, in the presence of two subscribing witnesses, on this 3rd day of August, A. D. 1911.
